UNITED STATES PATENT OFFICE.

KARL KRAUTSCHNEIDER, OF INNSBRUCK, AUSTRIA-HUNGARY.

MEDICAL APPARATUS FOR INJECTING PURPOSES.

No. 913,297.

Specification of Letters Patent. Patented Feb. 23, 1909.

Application filed November 27, 1907. Serial No. 404,130.

To all whom it may concern:

Be it known that I, KARL KRAUTSCHNEIDER, subject of the Emperor of Austria-Hungary, residing at Innsbruck, in Tyrol, 5 Austria-Hungary, have invented certain new and useful Improvements in Medical Apparatus for Injecting Purposes, of which the following is a specification.

This invention has for its object to provide 10 medical apparatus for injecting purposes in which the medicine or the like to be injected may be kept in a sterilized state in compressible capsules each containing a charge or dose of exactly the correct quantity. From 15 these capsules, which are also sterilized, the charge can be introduced by means of the syringe directly and under aseptic conditions into the particular part of the body to be treated.

20 Figure 1 of the accompanying drawings shows by way of example one construction of apparatus embodying this invention in longitudinal section. Fig. 2 shows the injecting cylinder or body of the apparatus in 25 elevation. Fig. 3 shows a capsule adapted to keep medicine contained therein in proper condition.

The apparatus comprises a cylinder *a* having a cover *b* detachably fastened thereto as 30 by means of a bayonet joint or the like. Through a centrally arranged threaded hole in the cover extends a spindle which is formed with a screw of steep pitch and which is provided with a follower *d* at its inner end and 35 a milled head *f* at its outer end. The front end of the cylinder *a* has a split tubular extension *g* on to which is forced or screwed a disk *h* adapted to compress the extension *g* at its forward end.

40 The medicine capsule *i*, made of tin or other suitable material, is of such size as to be readily inserted into the injecting cylinder *a*, and, in order to enable it to be filled in a sterile manner, it is provided with a discharge and filling tube *j* which, as long as the 45 filled capsule is unused, is closed by a sealing cap *k* (Fig. 3).

When the capsule is to be used the cap *k* is removed and before the disk *h* has been 50 placed on the extension *g* the capsule is introduced into the cylinder *a* so that the small discharge tube *j* projects through the tubular extension *g* of the cylinder. By then 55 putting the disk *h* in place the tubular extension *g* is compressed around the tube *j* and

the capsule *i* thus held in place. The usual injection needle *l* can then be attached to the tube *j*. After putting on the cover *b* the capsule can now be compressed by means of the follower *d* and its contents injected into 60 the part of the body being treated.

In order to charge the capsules they may be connected to a vial containing the medicine by a piece of flexible tubing.

Claim.

1. In a syringe for injecting purposes the combination of a cylinder open at one end and having a split hollow extension at its other end, a compressible capsule for the substance to be injected, adapted to be 70 placed in said cylinder and provided with a tubular projection to pass through said hollow extension and protruding therefrom, means for compressing said hollow extension around said tubular portion, and means for 75 compressing the capsule in said cylinder.

2. In a syringe for injecting purposes the combination of a cylinder open at one end and having a split hollow extension at its other end, a compressible capsule for the substance to be injected adapted to be placed in 80 said cylinder and provided with a tubular projection to pass through said hollow extension and protrude therefrom, means for compressing said hollow extension around 85 said tubular portion, a cover for the cylinder adapted to be fastened onto the open end thereof, a screw passing through a threaded hole in said cover and provided with a follower for compressing the capsule in said 90 cylinder.

3. In a syringe for injecting purposes, the combination of a cylinder open at one end and having a split hollow extension at its other end, a compressible capsule adapted to be placed in said cylinder and provided with a tubular projection to pass through said hollow extension and protrude therefrom and adapted to receive an injection point, such as a hypodermic needle, means for compressing said hollow extension around said 100 tubular projection, and means for compressing the capsule in said cylinder.

In testimony whereof I have hereunto set my hand in presence of two subscribing witnesses.

KARL KRAUTSCHNEIDER.
